CLAIM

The ornamental design for a shelving as shown and described.

DESCRIPTION

FIG. 1 is a perspective view of a first embodiment of the shelving;

FIG. 2 is a front elevational view of the first embodiment of the shelving;

FIG. 3 is a rear elevational view of the first embodiment of the shelving;

FIG. 4 is a left side elevational view of the first embodiment of the shelving; the right side of which is a mirror image;

FIG. 5 is a top plan view of the first embodiment of the shelving; and

FIG. 6 is a bottom plan view of the first embodiment of the shelving.

FIG. 7 is a perspective view of a second embodiment of the shelving;

FIG. 8 is a front elevational view of the second embodiment of the shelving;

FIG. 9 is a rear elevational view of the second embodiment of the shelving;

FIG. 10 is a left side elevational view of the second embodiment of the shelving; the right side of which is a mirror image;

FIG. 11 is a top plan view of the second embodiment of the shelving; and,

FIG. 12 is a bottom plan view of the second embodiment of the shelving.

The broken line portions of the drawings are included to show portions of the shelving that form no part of the claimed design.

1 Claim, 20 Drawing Sheets
